UNITED STATES PATENT OFFICE.

LOUIS MAXWELL POTTS, OF BALTIMORE, MARYLAND, ASSIGNOR, BY MESNE ASSIGNMENTS, TO AUSTIN McLANAHAN, OF BALTIMORE, MARYLAND.

PUNCHING-MACHINE.

1,105,921.

Specification of Letters Patent.

Patented Aug. 4, 1914.

Original application filed June 17, 1909, Serial No. 502,785. Divided and this application filed April 1, 1910, Serial No. 552,915. Renewed April 17, 1914. Serial No. 832,629.

To all whom it may concern:

Be it known that I, LOUIS MAXWELL POTTS, a citizen of the United States, residing at the city of Baltimore and State of Maryland, have invented certain new and useful Improvements in Punching-Machines, of which the following is a specification.

This invention relates more especially to that class of punching machines which are used for punching blanks or sheets for controlling automatic telegraph transmitters, linotype, type-setting, type-casting and other machines whose operation is controlled or effected by means of a perforated or equivalent blank or sheet, the said invention having been originally embodied in an application for Letters Patent of the United States for improvements in telegraphy filed by me on the seventeenth day of June, 1909, Serial No. 502,785.

In order that my said invention may be clearly understood, I shall now describe in detail with reference to the accompanying drawings a specific embodiment thereof and later point out what I claim.

In the accompanying drawings, Figure 1, is a front view of a telegraph blank for automatic transmission as prepared by my said machine; Fig. 2, a diagram showing the system of code combinations employed in perforating a message blank; Fig. 3, a front view partly in section and partly in elevation of one form of the machine forming the subject of the present invention, many of the parts being omitted for the sake of clearness in the drawing; Fig. 4, a side elevation of said machine; Fig. 5, a side elevation partly in vertical section of said machine; Figs. 6 to 19, inclusive, details of the punching mechanism of said machine; Fig. 20, a top plan view of the lower portion of said machine showing those parts located in the bottom of the machine with the upper frame portion of the machine removed; Fig. 21, a top plan view partly in section on line 21^x—21^x, Fig. 5, showing the various operating clutches, the combination bars and related parts; Fig. 22, a back view of said clutches and connected parts, showing also the backing screw, a portion of the printer carriage and other related parts; Fig. 23, a detail side elevation partly in section, of the

spacing clutch; Fig. 24, a similar view of the lining clutch; Fig. 25, an end view of the normally stationary member of the lining clutch; Fig. 26, a similar view of the backing clutch; Fig. 27, a detail perspective view of the clutch pin of the spacing and other clutches; Fig. 28, a perspective view of some of the mechanism which operates with the said clutches to effect the operations of "spacing," "lining," "backing" and "blanking"; Fig. 29, a detail cross section through some of the sliding bars shown in Fig. 28, showing the relative positions of the loops carried by said bars and the arms with which they coöperate; Fig. 30, a fragmentary detail view partly in elevation and partly in section of the spacing clutch and its operating magnet, showing the connection between the two, and showing also the connection between the spacing clutch and the spacing screw shaft; Fig. 31, a fragmentary detail view partly in section and partly in elevation of the actuating bar mechanism showing the connection between this mechanism and the rocking shaft of the stripper plate of the punching mechanism; Fig. 32, a fragmentary detail view showing the connection between one of the links of the striker bars and the sliding bar which operates said striker bar; Fig. 33, a fragmentary detail view, partly in section and partly in elevation of the back of the magnet supporting frame with magnet armatures mounted thereon showing the spring arrangement for returning said armatures to their normal positions after operation; Fig. 34, an enlarged fragmentary perspective view of the combination bars together with a sliding bar and latch mechanism and related parts which coöperate with said combination bars; Fig. 35, an enlarged detail fragmentary elevation to illustrate the manner of supporting said combination bars; Fig. 36, a section on line 36^x—36^x, Fig. 35; Fig. 37, an enlarged detail perspective view showing the supporting frame and rods for the key levers; Fig. 38, a diagrammatic view showing the arrangement of slots in the combination bars; Fig. 39, a semi-diagrammatic view showing the arrangement of lugs on the actuating bars; Fig. 40, a diagram showing an arrangement of the circuit of the spacing magnet, and controlling contact device therefor; Figs. 41 to

44, inclusive, detail views of said contact controlling device, showing various steps in its operation, Fig. 45, a bottom plan view of the paper carriage removed from the machine; Fig. 46, an end elevation of said carriage; Fig. 47, a front elevation of the bracket of said carriage which carries the spacing screw nut and the backing roller; Fig. 48, a fragmentary horizontal section of one end of the paper feed roller of said carriage showing the lining shaft screw partly in section and partly in elevation; Fig. 49, a section taken on line 49^x—49^x, Fig. 48, looking to the left; Figs. 50 to 54, inclusive, details of the spacing and backing screws and some of their coöperating parts; Fig. 55, a detail side elevation showing the relation between the lifting bar lever mechanism and the cam which operates the same; Fig. 56, a detail view showing partly in section and partly in elevation the arrangement of gears for transmitting motion to the lining shaft, and the mechanism on the end of said shaft for rotating the same independently of the power mechanism; Fig. 57, a section on line 57^x—57^x, Fig. 56 looking to the left; Fig. 58, a section on line 58^x—58^x, Fig. 56; Fig. 59, a section on line 59^x—59^x, Fig. 56; Fig. 60, a detail semi-diagrammatic view to show the arrangement of the successive telegraph blanks on a continuous roll of paper; Fig. 61, a fragmentary detail top plan view to illustrate principally the arrangement of the cams for operating the blanking mechanism; Fig. 62, a detail view partly in side elevation and partly in section to further illustrate the mechanism whereby the said cams operate the blanking mechanism; Fig. 63, a detail view partly in section and partly in elevation to show the connection between the lining clutch and the shafts which carry said cam mechanism.

I shall first describe a form of perforated blank prepared by my said machine, and will then take up the description of the machine itself in detail. Such perforated blank is shown in Fig. 1, and in this particular case is a telegraph blank comprising a sheet of paper or other suitable material bearing, among other things, a message impressed thereon both in printed characters and code perforations, the said printed matter and code perforations being arranged in line-to-line form so that the intelligence reads from the end of one line to the commencement of the next line as on the ordinary printed page, each printed character occupying a position next above the code perforations corresponding thereto.

In addition to the code perforations which correspond to the printed characters—and I use the term "characters" to include letters, numerals, punctuation marks, signs and the like—there are certain other perforations, hereinafter more particularly described,

which act solely to control mechanical operations, such for example, as causing a machine to "space," to feed a blank up to a new line, to shift a carriage back to the commencement of its travel, and to feed a new blank into the operating position. The function of these last mentioned perforations, however, will be more clearly understood from the detail description of the machine itself.

The rows of circles along the two side edges of the telegraph blank, represent perforations employed in feeding the sheet in the machines, as will hereinafter more fully appear. The code perforations of these controlling blanks are arranged in prearranged combinations so that each combination shall represent a different "character" or certain operations as above pointed out. The present machine therefore must be so arranged as to select the combination of punches corresponding to such perforations to be effected.

The system of combinations upon which is based the arrangement of the code perforations on the message blank shown is clearly illustrated in the diagram Fig. 2. Referring to this diagram, let the line of characters and other signals extending horizontally across the top of the diagram represent the various transmittable characters and other signals. For all of these characters and the other signals indicated, there are eight code positions, indicated on the left in the diagram (Fig. 2) by the vertical zigzag row of eight round dots. These positions passing from the top to the bottom of the vertical row referred to, shall be called the *a*, *b*, *c*, *d*, *e*, *f*, *g* and *h* positions, respectively. Each of such code positions is determined by the vertical distance from each end of the row and by the horizontal position on either side of an imaginary line indicated by the dotted line *x*—*y*, passing vertically through said zigzag row. Each code character or signal is formed by one or more perforations occupying a different one or combination of such positions. For example, for the letter "A" the perforations occupy the *a* and *d* positions; for the letter "B," the *b* and *f* positions; for "C," the *b* and *g* positions, and so on through the alphabet. The numerals, "back," "line," "blank" and four other miscellaneous signals are, in the case shown, formed each by the combination of three positions. For example, the code numeral 1 is formed by perforations in the *b*, *e* and *h* positions; the "back" signal, which will be more readily understood later, is formed by perforations in *a*, *b* and *g* positions, and the dollar mark by the *d*, *e* and *f* positions. The punctuation marks and "space" signal occupy but one code position each. Such a system of combinations possesses a decided advantage over a system

where each signal is represented by one position only, or two positions only, or three positions only, in that the signals to be transmitted are not so long; and the perforations when arranged in the code positions 5 may be compressed into a smaller vertical space, the latter being an important consideration when the code perforations come between lines of printed characters. Such 10 a system has an advantage also over a system which uses all combinations in a promiscuous way, as the employing of the same number of positions or combinations for the numerals as for the characters, in that it 15 provides against errors and also for readily detecting them, all as fully pointed out in said application.

Passing next to the description of the machine itself (Figs. 3 to 63 inclusive) the 20 printing in this machine is effected by sending type 1, carried by pivoted bars 2 into engagement with a suitable inked ribbon 3, which passes in front of the paper 4, upon which the printing is done. This paper in 25 turn passes in front of a suitable platen 5, which may consist of a piece of rawhide or other suitable material clamped rigidly to the cross frame 6 of the machine by a flanged plate 7, held rigidly against said frame by 30 means of screws 8.

No particular form of ribbon or ribbon-feeding mechanism is claimed as a part of this invention, and as such mechanisms are well known it is unnecessary here to go into 35 a detailed description of this feature.

The punching is effected by causing lugs 9 on the type heads 10 of the striker bars 40 to drive punching pins through the paper. These lugs are arranged on said striker heads in such manner as to operate their 45 corresponding punches, that is, the lug or lugs on each striker bar head are in code formation corresponding to the perforations to be produced. For example, the striker 50 bar head for the letter "A" would have two lugs disposed so as to strike the anvils which operate the punching pins in the *a* and *d* positions, and so on with the other combinations. This punching mechanism is shown 55 in detail in Figs. 6 to 19, inclusive.

The punching pins comprise each a preferably cylindrical shank portion 11, the shearing end of which is serrated, as at 12, to more readily cut the paper. The shanks 55 of these pins pass through and are longitudinally slid able in holes 13 in a stripper plate 14, and in corresponding holes 15, in the upper end of a plate 16, screwed or otherwise made fast to the front plate 17 60 of the machine. These pins in the present machine are eight in number, staggered as shown so as to occupy a small space vertically. The positions occupied by these pins correspond to the code position of the 65 eight round dots forming the zig-zag row

at the left hand end of Fig. 2. Each of these pins is provided with an elongated head 18. The heads of these punching pins are prevented from turning by a small pin located as indicated at 18^a, Fig. 7. Resting 70 respectively upon these heads, are a series of eight anvils 19, pivoted upon stud 20 screwed into a plate 21 secured to plate 16 by screws 22 passing through slots 23 in plate 21. These anvils are so arranged that 75 their heads resting upon the heads of the punching pins, are adapted to be struck by the combination lugs 9, on the striker bar heads, and thus act to force the punching pins through the paper. Immediately after 80 the said pins have been forced through the paper, they are drawn back therefrom by means of the stripper plate 14, which at that time moves away from the paper, and, engaging the heads of these pins which 85 have been operated, carries them out of engagement with the paper. This stripper plate is slidably mounted on two forwardly extending pins 24, carried by the plate 16, the said stripper plate being for this purpose 90 provided with guide sleeves 25, which slide on said pins. A shearing plate 26 is located just in the rear of the row of holes through which the punching pins pass in the plate 16, and is provided with a similar 95 arrangement of holes 27, adapted to register with the shearing ends of the punching pins. This shearing plate is made fast to the frame 6 of the machine in any suitable way, the frame of the machine being cut away, as 100 at 28 to allow the punchings to fall into a pan or other suitable receptacle hereinafter more particularly referred to. The necessary motion is imparted to the stripper plate through trunnions 29 at its ends, which engage in vertical slots 30 in the upper ends 105 of lever arms 31, made fast to a rock shaft 32, journaled near one end in brackets 33 made fast to the front plate 17 and at its other end in the frame of the machine (see 110 Fig. 3). This shaft 32 is actuated through a lever 34, connected to certain power mechanism, which will be hereinafter more particularly described, through a pin 34^a working in a forked end 34^b of arm 34, there being 115 considerable lost motion between said fork and pin, thereby imparting but slight movement to arm 31 as compared with the movement of pin 34^a. (See Fig. 31).

In this punching mechanism no springs 120 are required to return the punches to their normal positions, and, therefore, when these punches are driven forward into the paper there is no resistance to be overcome; other than the friction of the pins and the resistance of the paper.

In some uses of the machine it is desired to print without perforating. This change may be effected in the present mechanism by a very simple adjustment. By loosening 130

the screws 22, and sliding the block 21 to the left, (Fig. 7), the anvils may be withdrawn from the path of the perforating lugs 9, on the striker bar heads, so that when a given striker bar is operated its type will be sent against the ribbon, but the lugs 9 will be rendered non-operative. The anvils are shown in this position in Fig. 12.

The striker bars 2 are, in the machine shown, supported in a semicircle upon a common fulcrum, consisting of a wire 35 sprung into a recess or groove 36 in the semicircular front plate 17 of the frame of the machine, the said striker bars being supported upon said wire by means of bearing lugs 37. Each striker bar moves in an individual guide slot 38 in the front plate 17. In the drawings all but one or two of the striker bars are omitted for the sake of clearness. These striker bars are all held in position on fulcrum wire 35 by means of a segmental plate 39 bolted to the plate 17 and provided with a rounded cut portion 40 to fit the radius of the supporting lugs 37 of the key levers. By removing one or more segment plates 39 at a time, the striker bars held by these sections may be removed without disturbing the others. In the position of rest the heads of the striker bars lie on a pad 17^a supported by a semicircular plate 17^b secured to the machine frame as shown most clearly in Fig. 3. These striker bars are suitably spaced and bent, as is well known in typewriter construction, so that they will be driven to a common center, the type head of each bar passing to the striking point through a guide slot 41 in guide plate 42, located just below the row of punching pins and made fast to the plate 16. Each striker has a rear extension or short lever arm 43, each of which extensions is pivotally connected to one end of an individual link 44 and each of these links is pivotally connected at its other end to an individual pin 45. Each of these pins is longitudinally slidable in a separate lug 46 of a series of sliding bars 47, there being one such sliding bar for each such striker bar, and one such lug on each sliding bar. The movement of pin 45 in its lug 46 is limited in one direction by nuts 48. On the side of lug 46 opposite nuts 48, the pin 45 carries a coil spring buffer 49 (see Figs. 5 and 32). A given striker bar is sent into the striking or operating position indicated in dotted line in Fig. 6, by the forward (left to right in Fig. 5) movement of its individual sliding bar 47 causing its lug 46 to engage nuts 49, thereby imparting longitudinal movement to pin 48 which, pulling through link 44, acts on short arm 43 to turn the striker bar on its fulcrum 35. A small amount of lost motion is allowed between spring 49 and lug 46 to allow the striker

bar 2 to travel ahead of the motion of sliding bar 47 in order to give a sharp blow. The lugs 46 uniformly increase in length as their distance increases from the center of the machine so that their heads lie in the arc of a circle, as most clearly shown on the left in Fig. 3. The sliding bars 47 are mounted in guide slots in bars 50 and 51, which extend transversely across the machine and are made fast to the side frames thereof.

The sliding bars 47 receive their motion from an actuating bar 52, which is at times positively connected to the individual sliding bars 47, by means of latches 53, one of which is pivoted on each of said sliding bars. The operative connection between the said latches and bar is formed by the latter engaging shoulder 54 on the heads of the individual latches (see Figs. 5 and 34). The actuating bar 52 is supported at its ends on bars 55 and 56, which are slidably mounted in plates 50 and 51 for movement back and forth in the machine. Such movement is imparted to said bars from a rock shaft 57, acting through crank arms 58 and links 59 connected to lugs 60 on the respective bars 55 and 56 (see Figs. 5 and 21). Rocking motion is imparted to said shaft 57 through crank arm 61, located on the end of said shaft outside the machine (see Figs. 4, 21 and 22), and connected by rod 62 to a crank disk 63, made fast to a spindle 64 formed on one end of the spacing screw hereinafter described. The shaft 64 receives its motion through sprocket gearing 65, 66, 67 (see Fig. 22), from a clutch hereinafter described, mounted on a continuously rotating shaft 68, which is geared from sprocket 69 fast thereon through the sprocket gearing indicated, or in any other suitable way, to a small electric motor 70, mounted on the frame of the machine. Obviously, any other suitable source of power, may be employed in place of the electric motor, but such a motor is preferred.

The selection of the particular latches 53 to be engaged by the actuating bar 52, is effected by means of a series of combination bars 71, coöperating with tail pieces 72 on the several latches. These tail pieces 72 pass transversely across all of the combination bars and normally rest in guide slots 73 in a plate 74, which extends across the machine and over the tops of all the tail pieces 72 (see Fig. 34). The latch tail pieces 72 are constantly pulled toward the combination bars by individual springs 75, secured to the latches and to depending brackets 76 on the slide bars 47.

The selection of the particular latches to be operated is effected by bringing into transverse alinement, beneath the tail piece of the latch it is desired to select, a row of slots 86 in the upper edges of the combina-

tion bars, thereby permitting the particular latch tail piece above said aligned slots to be pulled thereinto by spring 75. This causes the selected latch to turn on its pivot 5 and send its latch shoulder 54 into the path of the actuating bar 52 which in its forward travel, will engage said latch and thereby become positively connected to the slide bar 47 of the striker bar which it is desired 10 to operate.

The arrangement of the slots in the combination bars is most clearly shown in the diagram Fig. 38 which indicates enough of the length of said bars to illustrate the principle involved. For each of the *a*, *b*, *c*, *d*, *e*, *f*, *g* and *h* code positions there is a combination bar, and these are so slotted that by shifting said bars laterally in the code combinations required for the different characters or other signals, each such bar or combination of bars thus shifted causes an alinement of slots across all of the said bars. Thus, for the space signal the *d* bar alone 15 would be shifted, and this would effect an alinement of slots across all the bars. For 20 the letter (A) the *a* and *d* bars would be shifted, causing an alinement of a different combination of slots, and so on.

Each combination bar is moved forward 25 against the tension of an individual spring 87 each of which is secured at one end to a hook 85 on its combination bar, and all secured at their other ends to a bracket 89 secured to the bottom of side plates 77, 78 30 (see Fig. 3). These springs return the combination bars to their normal positions.

The alining of slots in bars for selective purposes is well known in the art, and I do not claim this feature broadly. The system 35 of combinations, however, upon which these bars are slotted is new and forms an important part of this invention. These combination bars are mounted between two side plates 77 and 78, made fast at their ends to 40 supporting bracket 79 secured to the side frames of the machine, the said bar being supported near their ends for longitudinal movement between said plates upon rollers 45 carried on a pin 81 supported in plates 77 and 78, the said rollers each passing through slots 82 in the combination bars. Between the combination bars are located 50 spacing washers 82 (see Figs. 6, 35 and 36). The plates 77 and 78 are provided respectively, with slots 84 and 85 registering with 55 each other and acting as hereinafter described as guides for the tail pieces of the said latches.

The latch tail pieces 72 do not normally 60 engage the tops of the combination bars, since they would thereby interfere with the longitudinal motion of said bars, but are held a short distance thereabove by means of a bar 90, which extends across the machine and normally engages all of said tail 65

pieces, holding them up out of engagement with the combination bars until it is necessary for said arms to engage the slots in said bars, when said bar 90 passes downward allowing the tail pieces 72 to follow it. 70 This releasing bar 90 is supported at its ends on arms 91 located near each side of the machine frame and made fast to rock shaft 92, extending across the machine and journaled in the side frames thereof (see 75 Figs. 4 and 21). The required motion is imparted to this shaft through the medium of a link 93 connected at one end to one of the arms 91 and at its other end to a lever 94 made fast to a stud shaft 95 passing 80 through the side frame of the machine and carrying at its outer end a lever 96 made fast thereon. The lever 96 has a shouldered head 97 which rests against a cam 98 made fast to the shaft 64 just outside of the frame 85 of the machine (see Figs. 4, 50 and 55). The manner in which the cam coöperating with the arm acts to raise the left bar will more fully appear from the description of the operation of the machine which will follow later. 90

The necessary shifting of the combination bars to bring their slots into proper alinement may be effected in the present machine either electrically or by the manual operation of the keys of a keyboard. The combination bars are operated electrically in the machine shown by a series of eight electromagnets 99, acting upon pivoted armatures 100, provided with arms 101, which extend 95 across the combination bars beneath them and engage lugs 102 on their lower edges. There is but one lug 102 on each combination bar, so that each of said bars is operated by its individual magnet 99. The electromagnets are supported by being mounted each in a separate cavity 103 in an iron casting 104 which extends transversely of the machine and which is shown most clearly in 100 Figs. 3, 5 and 20. 110

The armatures of the magnets 99 are returned to their normal positions after operation each by an individual coil spring 105 located each in a cavity 106 in casting 104 and pressing up against an arm 107 forming 115 an extension on each armature 100, the upward movement of arms 107 being limited by screws 108 (see Fig. 33). It will be readily seen that since there is one magnet 99 for each combination bar, these bars may 120 be shifted in various combinations depending upon the combinations in which the magnets are energized. The manner of energizing these magnets to effect the required combinations, however, forms no part of my 125 present invention and may be effected in any desired way.

The keyboard of the machine corresponds in its arrangement substantially to that of a standard typewriter keyboard, except in the 130

present machine there are certain additional keys employed. These will be described later.

The keyboard mechanism in the present machine comprises among other parts, a plurality of key levers 109 fulcrumed on rods 110 extending across the machine and supported at their ends in uprights 111 (see Fig. 37) carried by a supporting bracket 112 secured at its ends to the sides of the machine frame. The rods 110 are supported between their ends to prevent sagging, by uprights 113 on bracket 112. These rods are suitably spaced apart so as to give to all of said levers, though differing in length, substantially the same or a uniform movement at their ends 114. On the finger tip portions 115 of the keys are inscribed the characters and other signals employed.

20 The forward ends of the key-levers work in guide slots 116 in a plate 117 extending across the front of the machine, said key levers being normally held up against the top of said slots by springs 118 secured to 25 the ends 114 of the key levers (see Fig. 5) and to a stationary strip 119 extending across the machine.

The extreme left hand key lever (Fig. 20) is the same as any of the key levers, except 30 that instead of being provided with a finger tip portion such as 115 it connects to a space bar 121 which is supported near its ends upon levers 122 made fast to a rock shaft 123 journaled in the sides of the machine. 35 By pressing the space bar down at any point in its length, downward motion will be imparted to the outer end of the spacing key lever.

In some uses of the machine, as for example, when it is used as a combined telegraph transmitter and home recorder, it becomes necessary to lock the keys against operation at certain intervals. This is accomplished in the machine shown (see Figs. 5, 20 40 and 21) by providing each key lever with a lip 124, which rests either above or below (according to the position of the key lever), the beveled edge of locking bar 125, which extends transversely across all the key levers. Bar 125 is supported at its ends upon brackets 126, fast on shaft 127. Rocking motion is imparted to bar 125 through a link 128 connected to one of the brackets 126 and to the lower end of a rocking lever 129, 50 loosely mounted on a shaft 130. The lever 129 receives its motion from a rotating cam 131 made fast to the loose member of a clutch, hereinafter described, mounted on the constantly rotating clutch shaft 68. The 55 periphery of cam 131 engages a small wheel 132 mounted in the upper end of said lever, the said wheel being constantly held against the periphery of the cam by the tension of a spring 133. This locking mechanism being 60 essential in certain uses of the machine only,

may obviously be omitted from the machine when desired.

The key levers act to impart longitudinal motion to one or more at a time of a group of longitudinally slidable selecting bars 134, mounted between two side plates 135 and 136 which extend transversely across the machine and are supported at their ends by brackets 137 and 363, made fast to the sides of the machine (see Figs. 3, 5 and 20). 70 These bars are supported for sliding movement upon small rollers 138 mounted to rotate on pins 139 and extending through slots 140, near each end of the bars, said pins 139 being supported by the side plates 135 and 136. The side plates 135 and 136 are provided respectively, with guide slots 141 and 142 in which the ends of the key levers work up and down in operating. For the purpose of operating the bars 134, each key lever is 80 provided at its end with a beveled edge 143, while the bars 134 are each provided with cam edged lugs 144, so located as to be engaged in certain combinations by the beveled edges of the key levers and thereby 85 caused to shift said bars. In the machine as shown, these bars are shifted to the right, viewing the machine from the front.

The cam lugs 144 on the bars 134 are so disposed that the operation of a key lever 90 will result in the longitudinal shifting of one, two or three of such bars, according to the character or signal which said key lever represents. The manner of arranging these lugs on the selecting bars will be clear from 95 a study of Fig. 39 which shows in side elevation four of the bars removed from the machine. These lugs are simply arranged so that there will be the required number in 100 line with each key lever to shift that one 105 or combination of bars which corresponds to the character or other signal which the particular key lever represents. For example, the letter "A" is formed by the *a* and *d* combinations or code positions. Therefore, the *a* and *d* bars 134 would each have 110 a lug adapted to be engaged by the beveled edge of the "A" key lever, so that when the "A" key is operated the said *a* and *d* bars will be shifted. The space signal has but 115 one code position, viz., the *d* position. Therefore the key lever connected to the space bar would engage but one lug and that would be a lug on the *d* bar 134; and this bar only would be moved.

Each of the bars 134 is provided at one end with an upward extension or lug 145 and these lugs are disposed in line, respectively, with downwardly extending lugs 146, on each of said combination bars. Therefore, 125 when the selecting bars 134 move as described, they select and impart a similar movement to the proper combination bars and thereby bring the required slots thereof into alignment. The combination bars, in 130

being shifted as described, in addition to selecting the proper latch or latches for engagement with the actuating bar, also act to operate an electrical contact device which 5 controls the circuit of a magnet which in turn controls a clutch from which power is transmitted to the actuating bar. This contact mechanism is of peculiar construction and will now be described in detail, reference being had particularly to Figs. 40 to 44, inclusive. This mechanism comprises among other parts a lever 147, pivoted between two lugs 148, formed on the inside of a bracket 149, secured to the side of the machine. 10 This lever is adapted to engage at its upper end a pin 150, slideable in said bracket to operate an insulated contact spring 151, which is mounted between and insulated from two other contact springs 152 and 153. 15 The pin 150 has an insulating tip which prevents spring 151 from making electrical connection with the machine frame through said pin.

Pivottally connected to the side of lever 20 147 is a substantially U-shaped bracket 155. This bracket is provided with an extension or lip 156, which passes transversely across the ends of all the combination bars; and on the upper forward edge of this bracket 25 is a cam plate 157, which is adapted to be engaged, as hereinafter described, by a lug 158 carried upon bar 56 which is one of the reciprocating supporting bars for the actuating bar of the machine (see Fig. 21). 30 Contact is normally maintained between springs 151 and 152. When, however, one or more of the combination bars is shifted to bring about the required action of the machine, said bar or bars engaging the lip 156 35 on pivoted bracket 155 will force this bracket and therefore the lever 147 and pin 150 to the right (Figs. 40 and 44), thus breaking contact between the springs 151 and 152 and establishing contact between springs 40 151 and 153. The effect of this is to complete the circuit of the spacing clutch magnet 159, whereby the spacing clutch 160, indicated diagrammatically in Fig. 40 and hereinafter described in detail, is operated 45 and sliding bar 56 caused to travel forward. In thus traveling, the lug 158 first engages the cam plate 157 and thereby causes the pivoted bracket 155 to tilt up, raising its lip 156 clear of the ends of the combination 50 bars. The bracket 155 will continue to rotate upward on its pivots as the lug 158 advances toward the observer (Figs. 41 to 44) and when this bracket has thus rotated a short distance it will allow the lever 147 55 under pressure of spring 151 to be forced back to the position shown in Fig. 44. Then when bar 56 travels back, lug 158 is carried backward out of engagement the bracket 155 60 which then drops to its normal position.

65 In the drawings, the moving parts of this

contact device are shown in their normal position of rest in Fig. 40. Fig. 41, shows the positions of the parts after a combination bar has slid forward and engaged lip 156, pushing lever 147. Fig. 42 shows in top 70 plan the parts in the positions they occupy in Fig. 41. Fig. 44 shows the parts after the lug has passed across the upper face of bracket 155. Fig. 43 shows the parts in transit from position Figs. 41-42 to position Fig. 44. This contact device will prevent the engagement of the spacing clutch for more than one revolution, and therefore the repetition of an operation no matter how long a key is depressed or how long 80 the combination bars which have been operated remain in the operating position. The contact spring 152 is for use when the machine is employed as a telegraph transmitter and home recorder.

The spacing clutch magnet 159 is mounted in an extension of the general magnet supporting frame (see Figs. 20 and 30). This magnet is provided with an armature 162, pivoted as shown to the magnet frame. The 90 top of this armature is pivottally connected to a rod 163, which at its upper end is connected as shown to an arm 164 of a bell crank lever. The arms of this lever are formed on a sleeve 165 mounted loosely on shaft 130. 95 The other arm 166 of this lever extends upwardly from said sleeve and is provided at its upper end with a nose 167 which controls the operation of the spacing clutch (see Fig. 30).

The spacing clutch, as shown most clearly in detail in Fig. 23, comprises, among other parts, a collar 168, made fast on the shaft 68 and provided with radial teeth 169 cut in an annular extension 170 thereon. This collar 105 forms the fast member of the clutch. The loose member of the clutch consists of a hub 171 loosely mounted on the shaft 68 and provided with an annular channel 172 formed between two annular flanges 173, and with an extension to which is made fast the sprocket wheel 67 hereinbefore referred to. This sprocket wheel is geared as described to the sprocket 65 on the shaft 64, which, acting through the connecting rod 62 and associated parts hereinbefore described, transmits the necessary motion to the actuating bar 52. The fast and loose members of this clutch are at times coupled together by means of a connecting pin 174 mounted in rectangular 110 openings in the flanges 173 for sliding movement laterally of the hub. For this purpose pin 174 has cut in one end a series of teeth 175 which are adapted to engage the teeth on the fast clutch member 168. This connecting pin at its end opposite its teeth is under tension of a spring 176, which is in turn fast to the hub 171. The action of this spring is to normally force the pin 174 toward the fast 115 clutch member and thus normally tend to 120

125

130

couple the two members. The fast and loose clutch members are disengaged by shifting pin 174, under the tension of its spring 176 out of engagement with the teeth of the constantly rotating or fast member, and this is effected by causing the nose 167 on the end of the lever 166 to engage a cam surface 177 on the clutch pin and thus shift it back against the tension of spring 176. This pin is cut away as at 178 to receive nose 167 (see Fig. 27). The normal position of this nose is in engagement with pin 174, hence the loose member of the clutch is normally uncoupled from the constantly rotating member. Nose 167 is normally forced toward the clutch under tension of a spring 179 acting on a tail piece 180 of the clutch magnet armature.

Contacts 181 and 182 operated by insulating pin 183 on the tail piece 180 of the armature of the spacing magnet are brought into use when the machine is employed as a telegraphic receiver. Further description of these parts in the present specification is therefore unnecessary.

25 The paper carriage of this machine comprises among other parts two end frames 184 and 185 connected by brace rods 186 and 187 and by bar 188 extending across the bottom of the carriage. For detail views of the carriage see Figs. 45 to 49. The paper to be printed on or perforated is preferably supplied to the machine in the form of a continuous sheet from a roll wound on a core 189 (Fig. 5) which is rotatably supported upon a rod 190 passing through and supported by the end frames of the carriage. This rod is provided at one end with a knob 191 fast thereon, and at its other end is screw-threaded to receive a removable knob 192 by which the said rod is retained in the carriage. By removing knob 192, rod 190 may be withdrawn and the paper core removed and a fresh roll placed in the carriage. Made fast on the cross bar 188 of the carriage is a bracket 193 which is slidably mounted on a rod 194 which extends across the machine.

50 The sides frames of the carriage are provided with extensions in which are journaled the ends of a paper feed roller 195, through the longitudinal axis of which passes the lining shaft 196. The roller 195 is supported on the shaft 196 by bushing 197, fitted into and made fast to each end of the roller. These bushings are free to slide longitudinally of the shaft, but each carries two keys 198 which engage longitudinal slots 199 in the shaft 196, thereby permitting the roller 195 to travel longitudinally of the shaft, but holding it against rotation relative to said shaft.

60 The paper feed roller 195 carries near each end a series of equally spaced tapered pins 200, the office of which is to engage the marginal perforations in the paper and thus, by

the rotation of the roller, to positively and uniformly feed the paper through the machine. The distance between the centers of the successive holes of the marginal rows in the paper must be identically the same 70 as the distance between centers of successive pins in the two rows at the ends of the cylinder.

Extending alongside the paper feed roller is a presser roller 201 journaled in uprights 75 202 pivoted to extensions on the side frames of the carriage. This roller presses against the paper under tension of springs 203, and holds it firmly against the paper feed roller. Extending from one of the side frames to 80 the other across the bottom of the paper carriage is a supporting plate 204 in which is adapted to rest a small pan 205 or other suitable receptacle to catch the punchings as they fall from opening 28. 85

201^a indicates a knife-edge plate extending longitudinally across the top of the paper feed roller and made fast to the side frames of the carriage. This may be used to assist in tearing off the message blanks 90 as they pass from the machine.

The lining shaft 196 is journaled at its opposite ends in upright extensions of a frame 206 which extends across the machine and is made fast to the sides thereof. (See 95 Figs. 4 and 56). On one end of this shaft is made fast a star wheel 207, which coöperating with a roller 208, held against its periphery by a lever 209 under tension of spring 210, holds the shaft against slipping 100 from certain definite positions to which it is rotated. This is particularly important when the machine is used for perforating message blanks for automatic transmission, since it is important that there be a definite 105 and constant relation between the marginal perforations in the paper and the code perforations made by the machine.

The mechanism for operating the lining shaft whereby the paper is fed up one or 110 more lines will be described after the description of the carriage spacing mechanism.

The carriage is caused to travel step-by-step across the machine from right to left 115 to effect the proper spacing of the characters, words or other signals, by means of a rotating screw 211, the threads of which engage those of a nut 213 on the carriage. This screw, which extends across the machine and is located under the paper carriage, is of peculiar construction and is shown most clearly in the detail views Figs. 50, 51 and 52. It is cut with a triple thread 120 212, which is removed for something more 125 than two-thirds of its circumference. The nut 213 is also provided with a corresponding triple thread (see Figs. 45, 46 and 47). This nut is supported for sliding adjustment on two rods 214, which pass through 130

it and are made fast in the bracket 193 of the carriage. The nut may be adjusted on said rods by screws 215.

The spacing screw 211 is rotated one revolution for each space, and for this purpose is driven by sprocket 65 mounted fast thereon and geared to sprocket 67 of the spacing clutch, which has been described.

The lining shaft, at its end opposite the star 207 wheel, is provided with a reduced extension 216 (see Fig. 56), upon which is mounted a sprocket 217, through which power is transmitted to drive the said shaft. This sprocket is loose on the shaft, but is connected to drive the same through pins 218, made fast to a longitudinally slidable sleeve 219, said pins being adapted to pass into holes in the said sprocket. The sleeve 219 connects with the shaft extension 20 through a pin 220 fast to the said sleeve and adapted to move in a slot 221 in the shaft extension. The sleeve 219 is normally held in the position shown in Fig. 56, under the tension of a coil spring 222 held between a shoulder on the interior of the sleeve and a nut 223 on the end of the shaft extension. The purpose of this arrangement is to allow of the rotation of the lining shaft by hand independently of its regular power mechanism. To do this the sleeve 219 is pulled to the right, in Fig. 56, thus disengaging the pins 218 from the sprocket 217, when the lining shaft may be rotated independently of said sprocket. For the purpose of operating this sleeve it may be provided with a milled head 224. The sprocket 217 of the lining shaft receives its power by being geared to a small sprocket 225, fast on an elongated sleeve 226, mounted upon a longitudinally slidable countershaft 227. This countershaft is connected to the sleeve 226 by means of a pin 228 on said shaft engaging a slot 229 on the interior of said sleeve. The shaft 227 receives its power from a sprocket 230 made fast to a sleeve 231, also mounted on said countershaft. This countershaft is slidable longitudinally through the sleeve 231, but is always connected to rotate therewith by means of a pin 232 on said shaft engaging an elongated slot 233 formed on the interior of the sleeve 231.

The sprocket 230 is the main driving sprocket in the system of gears shown in Fig. 63, and, acting through the pin and slot connections, in the positions shown in Fig. 56, transmits power to the sleeve 226 and thence to the lining shaft without being transmitted through the intermediate gear 234, the office of which will hereinafter be described. With this train of gearing, the spaces between the lines of printed matter will be sufficient to allow the perforations to come between the printed matter. When, however, it is desired to print without perforating, it is not necessary that the distance

between successive lines of printed matter shall be so great. The changing from the wider to the narrower line spacing is effected in this machine by shifting the countershaft 227 to the left, thus changing the speed relation of the gears which drive the lining shaft. When the countershaft is thus shifted, the pin 228 thereon passes out of engagement with the sleeve 226 and into engagement with a slot 235 on the interior of the collar 236 of sprocket 234, loosely mounted on the countershaft. This sprocket 234 is in turn geared to a sprocket 237 mounted on a stud shaft 238 secured to the side frame of the machine. The sprocket 237 is made fast to a sprocket 239, which is in turn geared to sprocket 240 fast on sleeve 226. Therefore, when power is applied to the countershaft 227 from sprocket 230, this power will not be transmitted directly to the sleeve 226, but indirectly through sprockets 234, 237, 239 and 240, which will cause a smaller rotation of the sleeve 226 and therefore a smaller rotation of the shaft 196 for each lining operation. The countershaft 227 is provided with a knob 241 by which it may be shifted, and is held in its two operative positions by means of a ball 242 which may rest in either of two cavities 243 or 244 in the shaft according to which of the two said positions the shaft occupies, said cavities being provided with slanting sides, as shown. The ball is mounted in a hole in the collar 231 and is retained therein by means of a spring 245. The sprockets 217 and 225 and their chain may be inclosed in a gear case 246 mounted on one end of the frame 206 as shown in Fig. 3. The main driving sprocket 230 of the lining countershaft is geared to a sprocket 247, made fast on an extension of collar 248 of the hub 249 of the lining clutch 250, shown in detail in Figs. 24 and 25. This clutch is the same in general principles as the other clutches, but is modified somewhat in construction to adapt it to its slightly different operation. The normally loose members of the other clutches remain coupled up for one revolution at a time, while the normally loose member of the lining clutch remains coupled for only a quarter revolution at a time, when feeding the paper up for the successive lines. For this reason, the lining clutch is provided with one clutch pin 251, having teeth 252 adapted to engage with teeth 253 on clutch member 254 fast on shaft 68, as in the case of the spacing clutch, and three additional pins 255, which are substantially the same as the clutch pin 251, except that they have no teeth and act merely as disengaging devices to separate the pin 251 from the fast member of the clutch. All of said clutch pins must therefore be operatively connected together. This is effected by means of a flange 256, engaging a recess 257 in each of said

pins, the said flange being formed on one end of a collar 258 slidable longitudinally on an extension of the clutch hub 249 which is loose on the shaft 68. This collar is normally pressed toward the constantly rotating clutch member 254 by means of a coil spring 259 held between the flange 256 and a flange 260 on a collar 261, fast on the clutch hub extension 248. The sprocket wheel 247 is held fast between collar 261 and a collar 262, screwed on the end of the extension 248 of the clutch hub. The pins 251 and 255 are each provided with an opening 263, one of the edges of which has a cam face 264 just as in the case of the pin shown in Fig. 27. Normally resting in the opening 263 of one of these clutch pins, by which the teeth of pin 251 are normally disengaged from teeth 253 of the normally rotating clutch member, is a nose 265 (Figs. 21 and 28) carried on the upper end of lever 266 which is fulcrumed by means of sleeve 267 for angular movement on shaft 130. This lever is pulled toward the lining clutch by spring 268 secured at one end to lever 266 and at its other end to a stationary rod 269 extending across the machine (see Fig. 28).

Pivoted on lever 266 are two arms 270 and 271, one of which is pivoted to each side of said lever, as shown most clearly in Figs. 28 and 63. The forward end of arm 270 extends through a loop 272, consisting of a metal strip made fast to that slide bar 47 which operates the striker bar which will perforate the paper with that combination of perforations corresponding to the lining signal. The arm 270 is provided with a shoulder 273, the top of which is normally held in engagement with the under side of the top of loop 272 by the tension of a spring 274. The other arm 271 pivoted on the lining clutch lever is provided with a shoulder 275 similar to the shoulder 273. The tail of arm 271 is normally held under tension of spring 276 up against the under side of the top of a loop 277 formed on an extension 278 of an arm 279 pivoted to a lever 280 integral with a sleeve 281 made fast to shaft 130. Arm 279 is limited in its vertical motion by a stationary loop 279^a secured to the bar 50 and surrounding arm 279 (see Fig. 28). The upper edges of both arms 270 and 271 are normally held up toward the under side of a yoke 282 made fast to slotted bar 50 and provided with a cam plate 283 adapted under conditions herein-after described to engage the rear of shoulders 273 and 275 and depress the forward ends of arms 270 and 271. The function of lever 280 and its connection through loop 277 with arm 271 is to operate the lining clutch when either the backing or blanking or both mechanisms work. This will more readily appear later. There is also fast on

sleeve 281 an upright lever 284 having at its upper end a nose 285 adapted to control the operation of the backing clutch 286 in just the same way that nose 167 controls the spacing clutch. The spacing and backing 70 clutches being substantial duplicates, a detail description of the latter is unnecessary in view of the preceding description of the spacing clutch. The lever 284 is pulled toward the backing clutch under tension of 75 spring 287 secured to said lever and to rod 269. (See Fig. 28). The normally stationary member of the backing clutch carries a sprocket wheel 288 fast thereon, and this sprocket is geared to a sprocket 289 which drives the backing screw (see Figs. 22 and 50). The function of this backing screw is to send the paper carriage back to the commencement of its travel after it has advanced a part or all of the way across the 85 machine. This backing screw is shown most clearly in Fig. 50, consists essentially of cylinder 290 extending transversely of the machine below the carriage and having upon its circumference a raised spiral 291 which is adapted to engage a small roller 292 rotatably mounted on the bottom of the carriage supporting bracket 193. (See Fig. 45). This spiral has a constant pitch except for one revolution near one end, where the pitch 95 decreases, as at 293 to zero, in less than one revolution. At this end the screw is provided with a flange 294 which acts as a stop for the roller 292. It is evident that as this screw rotates in one direction, its spiral engaging roller 292 will push the carriage along. The direction of this rotation is such as to return the carriage to its starting point. The cylinder 290 of this screw is fast on a shaft 295 which extends across the machine 100 beneath the carriage and is journaled in the sides of the machine. This backing screw is driven, as before stated, by power applied to sprocket 289. This sprocket, however, is not itself connected directly to the backing 105 screw, but is fast on sleeve 296, which is loosely mounted on the shaft of the backing screw (see Fig. 50). This sleeve 296 carries a radial pin 297 which is adapted at times to engage a lateral pin 298 made fast to a 110 sleeve 299, slidable longitudinally on shaft 295, but held against rotation thereon by pin 300, engaging slot 301 in said sleeve. The sleeve 296 carrying sprocket 289 is held against lateral movement toward the backing screw by means of collar 299^a fast on shaft 295. The sleeve 299 is provided with two annular flanges 302 between which extends the fingers 303 of an arm 304 forming an extension on a sleeve 305 mounted loosely 115 on the spacing screw shaft. This sleeve is provided with a cam projection 306, which fits normally into a correspondingly shaped recess in a sleeve 307, made fast on the shaft of the spacing screw 211. The sleeve 305 is 120

125 130

forced in the direction of sleeve 307 under tension of coil spring 308 on the spacing screw shaft. From this construction it will be seen that when rotation clockwise is imposed to the spacing screw shaft 211 the cam projection 306 will ride upon the cam surface or sleeve 307, the sleeve 305 being caused thereby to be shifted laterally to the left. This shifting, by virtue of the connection of the arm 304 with sleeve 299 shifts said sleeve also to the left thus removing pin 298 from the path of pins 297. This disengages the backing screw shaft from its driving sprocket 289, and leaves it free to be rotated by the roller 292 on the carriage, in the forward travel thereof.

If the backing screw remained all the time geared to its power clutch, the roller 292 striking the spiral 291 on the forward movement of the carriage would not only stop the carriage, but the backing screw would try to rotate the backing clutch loose member backward, hence it is essential that the backing screw be absolutely free while the carriage is passing forward. Directly after each spacing operation, however, the backing screw becomes coupled up to its power sprocket 289 by the returning of the sleeve 305, under tension of spring 308, to its normal position. In addition to the decreasing pitch of spiral 291 at the righthand end of the backing screw, I may provide any suitable shock-absorbing means for lessening the jar occasioned by the carriage reaching the end of its back travel. In the drawings (Figs. 22 and 50) I have shown for this purpose a spring 309 made fast to a collar 310, by means of a screw 311 adjustable on the shaft 194. The spring 309 engaging the bracket 193 of the carriage takes up the shock.

Since levers 284 and 280 are fast on the same sleeve 281 it will be seen (see Fig. 28) that when lever 284 is rocked to couple up the backing clutch, the lever 280 will be rocked in the same direction, pulling arm 279 with it. Loop 277 on this arm being normally in front of the shoulder 275 as shown in Fig. 28, will then cause the lever 266 of the lining clutch to withdraw its nose 265 from that clutch starting the normally stationary member of that clutch to rotating and therethrough operating the lining clutch. It will therefore be seen that each time the carriage is sent back to its starting point it automatically feeds the paper up at least one line. In some cases the paper is fed up the distance of several lines, an operation herein referred to as "blanking", and which will now be described.

Pivoted to the actuating lever 284 of the backing clutch is an arm 312, the forward end of which extends through a loop 313 made fast to one of the sliding bars 47. (See Fig. 28.) This arm 312, like the arm 270

is provided on its upper edge with a shoulder 314 normally held up against the under side of the top of loop 313 under tension of spring 315.

The loop 313 striking the forward edge 70 of shoulder 314 on the back stroke of the sliding bar, as hereinafter more particularly described, rocks arms 284 back against tension of spring 287 thereby causing the nose 285 to be withdrawn from the clutch pin of 75 the backing clutch. This causes the loose member of the backing clutch to be coupled to the normally rotating member, which latter transmits, through sprockets 288 and 289, (see Fig. 22) rotation to the backing 80 screw 290, which screw thus rotating will send the carriage back to the commencement of a line.

The fast and loose members of the backing clutch are dis-engaged from each other 85 when the carriage has reached the end of its travel by the nose 285 on the backing clutch lever again engaging the connecting pin of that clutch. This is brought about by cam 316 (Figs. 3, 45, 46 and 47) fast on 90 the bracket 193 of the carriage tripping a dog 317 fast on a spindle journaled in bracket 318 on the frame of the machine, and made fast at its end opposite dog 317 to one end of a lever 319 which at its other 95 end is pivotally connected to a link 320 pivoted to arm 312. It will be seen that when the cam 316 on the carriage trips the dog 317, this will force lever 319 down, and this in turn acting through link 320 will force 100 the arm 312 down and thereby remove its shoulder 314 from engagement with the edge of the loop 313, thus allowing the clutch lever 284 to be pulled by spring 287 into engagement with its clutch pin. This 105 operation will be hereinafter more fully described.

When the machine is employed to prepare message blanks for automatic transmission, it is desirable to have the paper 110 which is fed to the machine in the form of a succession of connected telegraph blanks, as indicated in Fig. 60, each of said blanks having its individual heading. In such cases it is particularly desirable that the 115 paper shall be fed from one of such blanks to the next, past the headings, as quickly as possible—quicker than could be done by stepping the paper up by the regular lining mechanism alone. In the present machine 120 this is accomplished by certain mechanism auxiliary to the regular lining and backing mechanisms.

This mechanism (see Fig. 28) comprises among other parts, an upright lever 321 125 carried by a sleeve 322 mounted loosely on the shaft 130, to which lever is pivoted a horizontal arm 323 which extends through a loop 324 fast on that sliding bar 47 which actuates that striker bar corresponding to 130

the "blanking" signal. This arm 323 is also provided with a shoulder 325 on its upper edge which is normally held up against the under side of the top of loop 324 under tension of spring 326. In effecting this blanking operation, that one of the sliding bars 47 corresponding to the "blanking" combination takes up its motion, just as do any of the other sliding bars connected to the various striker bars. In thus moving, the sliding bar carries loop 324 in a direction toward the front of the machine (away from lever 321, Fig. 28), causing loop 324 to pass from engagement with shoulder 325. This allows the arm 323 to fly up a limited distance until its tail strikes the top of loop 324. Then when the sliding bar carrying loop 324 has nearly reached the end of its back travel, loop 324 engaging the forward edge of shoulder 325, will force arm 323 backward. This rocks lever 321 back, and this lever engaging an extension 327 on the lining clutch lever will rock that lever back, thereby withdrawing its nose from the lining clutch and thus causing the fast and loose members of that clutch to become coupled together. This puts the lining mechanism into operation. The loop 324 abutting against shoulder 325 will continue to hold the lever 266 back so that its nose will be out of engagement with the lining clutch, thus allowing the lining mechanism to continue feeding the paper up in the machine until some other mechanism acts to disengage the forward edge of the shoulder 325 from the loop 324. This is brought about by causing a cam link 328 (see Figs. 61 to 63) on a sprocket chain 329 to engage and force downward the end of a lever 330 which transmits, through a link 331 connected thereto and to the end of the arm 323, downward motion to said arm thereby releasing the forward edge of shoulder 325 from engagement with the edge of loop 324, allowing arm 323 to pass forward through said loop. This allows nose 265 to return to engagement with the connecting pin of the lining clutch and to thus uncouple the loose from the fast member of the clutch, thereby stopping the lining mechanism.

The sprocket chain 329 is mounted on the sprocket 240 on the sleeve which drives the lining shaft, and on sprocket 239 fast on a sleeve with sprocket 237, said sleeve being mounted loosely on stud shaft 238 made fast to the side of the machine frame as before described.

When a certain number of lines have been printed and perforated on a blank, the blanking mechanism may operate automatically to bring a fresh blank into position. For this purpose sprocket chain 329 is provided with a second cam link 332 arranged to travel in the path of an extension or wing 333 on an upright lever 334, which is fast

at its lower end on a sleeve 335 mounted loosely on a stud shaft 336 secured to the side of the machine. The cam 332, however, is so disposed on the chain that it will travel past lever 330 without engaging it. 70 The other end of sleeve 335 is made fast to a downwardly extending lever 337 which is flexibly connected through a link 338 to the end of arm 323. After a given number of revolutions of the lining shaft the cam 332 75 will be brought into engagement with wing 333 and striking this wing will force lever 334 in the direction of the travel of said cam, thus forcing lever 337 in the direction of the arrow Fig. 28. This lever in turn 80 forces arm 323 in the direction to operate the blanking mechanism as described. The operation of this automatic blanking is then stopped when cam 328 strikes the end of lever 330 after the lining shaft has made a 85 sufficient number of revolutions to bring the next blank into proper position.

Whenever the blanking key is operated or whenever the combination of magnets 99 corresponding to that operation are energized, the carriage will automatically be sent back to the commencement of a new line. For this purpose, the blanking lever 321 (Fig. 28) is provided with a horizontal extension or arm 339, which passes in front 95 of the blanking lever 280. Therefore, when the lever 321 is moved by arm 323 to operate the lining shaft, arm 339 carried by lever 321, will engage lever 280 of the backing mechanism, and cause this arm to transmit through sleeve 281 of the lever 284 the necessary motion to remove nose 285 from the backing clutch and thereby allow the normally loose member of said clutch to become coupled to the rotating member, 100 transmitting the necessary motion to the backing screw.

It is important that during these operations of "lining" and "backing" that the spacing mechanism shall not operate. This is effected by a locking device (see Figs. 28 and 30) located near one end of shaft 130 and consisting of a latch 340, pivoted at one end on a stud shaft 341 made fast to the machine frame, and connected by means of a link 342 with an arm 343 fast on a collar 344, which is in turn made fast to shaft 130. The end of latch 340 opposite its pivot is provided with a shoulder 345, which, when the arm 343 is rotated downward, is brought 110 into the path of a pin 346 on the lever 166 of the spacing clutch. Therefore, whenever the levers 280 or 284 are moved to start the backing mechanism, they rotate shaft 130 and this shaft being fast to collar 115 344 sends latch 340 downward, thus pulling the shoulder 345 of said latch into the path of pin 346, thereby locking the lever 166 against movement away from its clutch. To prevent jamming, the arm 343 is connected 120 to

to link 342 by pin and slot connection 342^a and 342^b, the slot being held down against the pin by spring 342^c. Therefore, if the lever 166 is thrown to the left (Fig. 30) when the arm 343 rotates, this will merely extend spring 342^c.

The loose member of the backing clutch is provided with a cam surface as indicated by dotted lines in Fig. 26. The object of this is to keep the actuating lever of the backing clutch out during an entire revolution so that arm 343 will not return to its normal position and thereby release the locking latch 340 before the backing clutch has finished revolving.

When the key-locking mechanism is used, an additional clutch 347, which shall be designated the "clapper" clutch, is employed. This clutch is a substantial duplicate of the spacing clutch, except that where the spacing clutch carries the sprocket wheel 67 fast on the loose member of the clutch, the clapper clutch carries the cam disk 131. The actuating lever 348 of the clapper clutch is provided with a pin-engaging nose 349 (see Figs. 21 and 28) which forms one arm of a bell-crank lever provided with a collar 350 mounted loosely on shaft 130. The other arm 351 of this lever is secured through an upright arm 352 to the top of pivoted armature 353 which is operated by electro-magnet 354 mounted in a cavity 355 in the magnet frame, as in the case of the spacing magnet. (Fig. 5.) The armature of this magnet is normally held in the raised position by spring 356. This armature, like the armature of the spacing magnet, has a tail piece 353^a which carries an insulating pin 353^b adapted to operate contacts 353^c and 353^d.

The frame of the machine may be of any desired construction. In the form shown, however, it comprises a base portion 377 and an upper portion 378 removably secured to the said base portion, the latter carrying the magnet frames, the key-board mechanism including the selector bars, and the small electric motor which drives the machine, while the clutches, striker bars, carriage mechanism and other parts are located in the upper frame portion. By making the frame separable in this manner the parts are rendered accessible.

The operation of the machine as thus far described is briefly as follows: It shall be assumed that a fresh paper blank has been fed into the machine to occupy the proper position for the commencement of the preparation of a message blank such, for example, as shown in Fig. 1, and that the machine is operated manually from the key-board, and, further, in order to bring into operation as much of the mechanism as practicable it will be assumed that the key-board is employed as a normally locked key-

board, bringing into operation the "clapper" mechanism. This operation can be followed best by referring principally to Fig. 5. The clutch shaft 68 is continuously rotated by the motor 70 and the clapper magnet 354 is energized at regular intervals by the completion of an electric circuit to be described later.

Each time this magnet becomes energized it draws its pivoted armature which removes the nose 349 of the clapper clutch 347 from the connecting pin of that clutch, but magnet 354 being energized only instantaneously, nose 349 will fly back to the path of the clutch pin immediately after receding therefrom. The effect of this is to cause the normally loose member of said clutch to become coupled to the fast member thereof for one revolution only, since nose 349 will engage its clutch pin and disengage the clutch members just as soon as the said pin comes around to the nose again.

This causes cam 131 to rotate one revolution and in so revolving it acts upon the upper end of lever 129 to send the lower end of that lever forward and thus rock the locking bar 125 out of the path of the lips 124 of the key levers, thereby allowing the end 143 of that key which is pressed down to rise, the said locking bar immediately returning to its original position thereby locking the said keys, by passing beneath the lip of the operated key and over the lips of the keys not operated. The effect of this operation of the key is to bring its cam surface 143 into engagement with that row of cam lugs on the selector bars 134 immediately in line with the edge of the key operated, thus transmitting lateral motion to one, two or three of said bars, as the case may be, depending upon the combination of such bars

representing the character which is to be impressed on the paper. These selector bars in thus being shifted, act through the lugs 145 on their ends, as described, to shift a corresponding number of combination bars 71 to the right, (see Fig. 3) viewing the front of the machine. These combination bars, in being thus shifted, strike the lip 156 on the lower edge of the pivoted bracket 155 of the electrical contact device (see Figs. 40 to 44) causing the central spring 151 of said device to engage spring contact 153, thereby completing a circuit, which energizes the spacer magnet 159, (see Fig. 30).

The spacing magnet then pulls down its armature 162, the effect of which is to pull the nose 167 of the lever 166 of the spacing clutch out of engagement with the clutch pin of that clutch, thus allowing the fast and loose members of said clutch to become coupled together. The circuit of the spacing magnet, however, is broken immediately after it is completed, by the operation of contact device, Figs. 40 to 44, as hereinafter described, thus allowing the nose of the

130

spacing clutch lever to fly back to the path of the clutch pin immediately after coupling up the clutch members. Therefore, when the clutch pin rotates one revolution it will again engage nose 167 and uncouple the clutch. The normally loose members of the spacing clutch therefore, rotate one revolution. In thus rotating the normally loose spacing clutch member 171 (Fig. 23) rotates sprocket 67 fast on said member and through this sprocket rotation is communicated to sprocket 65 on the shaft of the spacing screw, which is thereby started to rotate. The rotation of the spacing screw shaft causes the rotation of cam 98 mounted fast thereon, which cam is rotated in the direction of the dotted arrow, Fig. 4. Directly after this cam commences to rotate the latch head 97 on lever 96 will drop 20 from the elevated portion of said cam down to a portion thereof considerably nearer its center. When this happens the releasing bar 90 under the latch tail pieces 72, acting through its connection with the lever 96 will be allowed to descend, thereby allowing that 25 one of the tail pieces 72 which is above the row of alined slots in the combination bars corresponding to the combination for the character to be printed to be pulled by its 30 spring 75 into the alined slots. This causes the operated latch to send its engaging shoulder 54 (see Fig. 34) into the path of the actuating bar 52.

When rotation was imparted to the spacing screw shaft, this also imparted rotation to the crank disk 63 which, acting through connecting rod 62, crank arms 61 and 58 and links 59 starts the actuating bar forward. This bar, in its forward travel, engages the 40 head of the actuated latch 53, and continuing its forward movement pulls said latch along with it, and, since the said latch is pivoted to sliding bar 47 forward travel is imparted to this bar also. This movement 45 of the sliding bar pulls the link 44 forward, and this link acting on the short arm of the striker bar lever to which it is connected, swings this striker bar quickly on its pivot, thereby sending the type on its 50 head into engagement with the ribbon in front of the paper, also sending the lugs 9 on the striker bar head into engagement with those anvils of the punching mechanism corresponding to said lugs, thereby 55 causing the operation of corresponding punching pins. When the actuating bar moves forward as described, it carries with it through the connection shown most clearly in Fig. 31, the lower end of lever 34, causing 60 this lever to rock the shaft 32 so as to bring the stripper plate into the position shown in Fig. 11. After the perforation is effected and the actuating bar starts on its back travel, the same mechanism rocks the strip- 65 per shaft in the opposite direction, causing

the stripper plate to return those pins which have been actuated to their original positions as shown in Fig. 10. In this position they are withdrawn from the paper.

As the frame of the actuating bar moved 70 forward, lug 158 thereon engaged cam plate 157 of the contact mechanism shown most clearly in Figs. 40 to 44, thereby causing bracket 155 to tilt up and allow lever 147 to spring back to the position shown in Fig. 75 44, thus breaking the circuit of the spacing magnet.

As cam 98 continues its rotation the head 97 of the lever 96, (Figs. 50, 55 and 4) in engagement with the periphery of said cam, 80 for about the first half of the revolution of said cam passes over a portion thereof substantially concentric with its center, while the actuated latch 53 is in engagement with the actuating bar and the printing and perforating is being actually done. At about the end of the first half of the revolution of this cam the head of lever 96 passes on to a slightly raised portion of said cam, and then on to a portion of said cam which increases 90 rather rapidly in diameter. The effect of this is to send lever 96 rather rapidly downward for a short distance, thereby causing the releasing bar 90 to rise for a short distance rather suddenly. In thus rising this 95 bar engages the lower edge of the tail piece of the actuating latch and rather quickly lifts it. The head of lever 96 then comes into engagement with a portion of cam 98 which very gradually increases in diameter 100 terminating at shoulder 98' on said cam. The effect of this is to cause a more gradual rise of the bar 90 during the latter portion of its upper movement than at the beginning thereof. During the latter portion of 105 such movement the bar 90 has to engage and lift all the latch tail pieces, whereas during the first portion of its travel upward it has to lift one only of said latches. This is the end of the operations necessary to print and 110 perforate the character on the paper. As these operations are repeated, the carriage will travel step by step from right to left across the machine.

When the desired number of characters 115 have been formed on a line and it is desired to return the carriage to the commencement of a new line the backing key is operated. This key is just the same as any of the regular character keys, and is provided with its corresponding sliding bar 47, latch 53 and striker bar 2, the latter provided on its head with suitably arranged lugs 9 to cause the perforation of the paper with a code arrangement of perforations corresponding to 120 the "backing" signal which, as will be seen from the diagram Fig. 2, occupy the *a*, *b* and *g* positions. On the striker bars for perforating the spacing, lining, backing and blanking signals the type are of course 125 130

omitted. When this backing key is operated its sliding bar 47 passes first toward the front of the machine as do any of the other sliding bars and then travels back.

5 In thus moving forward said sliding bar carries loop 313 forward out of engagement with shoulder 314 on arm 312 (see Fig. 28). This allows the forward end of arm 312 to rise until it strikes the under side of loop 313. Then, when the sliding bar carrying said loop has nearly reached the end of its back travel, said loop will engage shoulder 314 and push arm 312 backward. This rocks lever 284 back, thus removing nose 285 from the pin of the backing clutch, thereby coupling the normally stationary or loose member of said clutch to the rotating member and communicating through gears 288 and 289 (see Fig. 22) rotation to the 10 backing shaft. This causes the carriage to be sent back to the commencement of its travel. When the carriage has about reached the end of its back travel, the lug 316 tripping dog 317 sends the lever 320 down, thereby releasing shoulder 314 from the upper edge of loop 313. This allows lever 284 to return its nose 285 to the backing clutch and thereby disengage the normally loose from the fast member of the 15 clutch, stopping the rotation of the backing screw. When lever 284 was operated to start the backing screw, said lever imparted through sleeve 281, angular movement to lever 280, and this lever acting through arm 279 and loop 277 and shoulder 275 on arm 271, also caused lever 266 of the lining clutch to withdraw its nose from said clutch, thereby causing the fast and loose members of said clutch to become coupled and 20 operate the lining shaft to feed the paper up a line. Directly after the withdrawal of the nose of the lining clutch from said clutch, shoulder 275 on arm 271, strikes cam plate 283. This causes the forward end of arm 271 to be sent downward, thereby removing shoulder 275 from engagement with the edge of loop 277. As soon as this happens the arm 271 becomes released and allows 25 spring 268 to send the nose 265 of the lining clutch lever into position to engage the next pin of said clutch. Since this clutch is provided with four such pins the normally stationary member of said clutch will be rotated but a quarter revolution before 30 it is disengaged in performing the regular lining operation. It will, therefore, be seen that when the carriage is sent back to the commencement of its travel the paper is automatically fed up a line.

35 If it is desired to pass to a new line without backing the carriage, this is effected by operating the lining key which, like the backing key, is provided with its corresponding sliding bar 47, latch 53 and striker bar 2, the latter carrying a suitable arrange-

ment of lugs to cause the paper to be perforated with such an arrangement of perforations as will represent or transmit the lining signal. This lining signal, as will be seen from the diagram Fig. 2, is formed by perforations occupying the *a*, *b* and *f* positions. When the lining key is thus operated its sliding bar 47 travels forward to effect the perforation of the lining signal and allows the forward end of arm 270 (see Fig. 28) 75 to rise and thereby place the forward edge of shoulder 273 in the path of loop 272. On the back travel of the sliding bar 47 connected to this loop, the said loop will strike the forward edge of shoulder 273 pushing arm 270 back and releasing the nose 265 from the pin of the lining clutch, thereby causing the normally loose member of said clutch to become coupled to the fast member which will then rotate the lining shaft. Directly after the nose 265 is thus withdrawn from the lining clutch, the shoulder 273 will engage cam plate 283, thereby disengaging said shoulder from the rear edge of loop 272, allowing the nose 265 to return to the 80 lining clutch in time to engage the next pin so as to stop the rotation of the lining shaft.

When it is desired to space without printing, and to perforate the paper with a perforation corresponding to the spacing signal, the space bar is operated, and this causes the shifting of a certain combination bar (the *d* bar Fig. 38) necessary to cause the alinement of a certain combination of slots in said bars, as in the case of any other 85 signal. This bar thus becoming shifted energizes, as before described, the magnet of the spacing clutch, thereby operating said clutch and causing the carriage to space as described. The alining of the slots in the 90 combination bars to represent this spacing signal permits the engagement of the latch on a sliding bar 47 to operate a striker bar 2, having a lug suitably arranged thereon to operate the punching pin corresponding 95 to the code arrangement for the transmission of a spacing signal.

The operation of feeding the paper up from one blank to a succeeding blank was fully described in the detail description of 100 the machine, and, therefore, need not be repeated here. In the foregoing operation of the machine it was assumed that the machine was manually controlled through the 105 keyboard.

If the machine is operated electrically, the bars 71 are shifted by the magnets 99, acting on said bars through their pivoted armatures engaging lugs on said bars as described. By energizing these magnets in certain combinations corresponding combinations of selector bars 71 may be operated. The rest of 115 the operation of the machine is the same as when controlled manually from the keyboard.

The extensions 357, on bars 134, contacts 358, 368, bracket 363, plug sockets 365 and 366 (Fig. 3) are parts which are used with the machine when it is employed as a combined keyboard telegraph transmitter and home recorder. Such transmitting mechanism, however, is not claimed as a part of this invention, so need not here be further described. The machine as a combined 10 telegraph transmitter and recorder is claimed in a co-pending application Serial No. 612,577, filed March 6, 1911, which is a co-divisional application herewith of my application Serial No. 502,785 hereinbefore referred to.

The machine here shown and described possesses many other novel features which are not necessarily limited to a punching machine, but which have to do more with a 20 telegraph receiver in a generic sense so far as the form of the record is concerned, or, in other words, irrespective of whether its record is a printed one, a perforated one, or a combination of the two, such features being claimed in the parent application Serial 25 No. 502,785, which application also contains claims to perforating mechanism, but as forming a part of telegraphic receiving mechanism.

30 The invention forming the subject of the present application relates to a punching machine *per se* whether used in a telegraph system or not, considered generically with respect to its initial operating means. The 35 specific initial operating means claimed in the present application, however, is keyboard or manual means as distinguished from electrical means operated from a distance as in the case of a telegraph receiver.

40 What I claim is:

1. A punching machine, comprising a plurality of punches, a plurality of pivoted striker bars for operating said punches and of greater number than said punches, each 45 of said strikers being provided with means to select predetermined punches for operation, and mechanism to operate said striker bars.

2. In a punching machine, the combination 50 with a plurality of punching pins, of a plurality of pivoted striker bars each having a striking head having lugs arranged thereon to operate a different one or combination of said pins, and means to operate said 55 striker bars.

3. In a punching machine, the combination 60 with a plurality of punching pins, a movable stripper plate, a plurality of pivoted anvils, one for each of said pins, said anvils adapted to lie in front of the respective punching pins, a plurality of striker bars each having a striking head arranged to engage a different one of said anvils or combination of said anvils and thereby oper-

ate corresponding punching pins, and means 65 to operate said striker bars.

4. A perforating machine, comprising a plurality of character keys, a plurality of punches of lesser number than said character keys, means controlled by said character keys to select a given combination of said punches for the respective keys operated, a plurality of pivoted striker bars adapted to operate said punches, and power operated means controlled by said selecting means to 75 operate said striker bars.

5. A punching machine comprising a plurality of punches, a plurality of pivoted strikers for operating said punches said strikers each having a head arranged to select predetermined punches for operation, power operated mechanism for operating said strikers, selective mechanism for selecting the desired strikers and coupling same to the power mechanism, and a keyboard 85 having keys greater in number than said punches and adapted to operate said selective mechanism.

6. A punching machine, comprising a plurality of punching pins, a plurality of pivoted striker bars for operating said pins and of greater number than said pins, each of said strikers being provided with means to select predetermined punches for operation, printing type carried on said striker bars, 95 and mechanism to operate said striker bars.

7. In a punching machine, the combination with a plurality of punching pins, a plurality of striker bars each having a striking head arranged to operate a different one 100 or combination of said pins, printing type carried on the striking head of said bars, power mechanism, means to operate said striker bars from said power mechanism, and means to select the striker bars to be 105 operated.

8. A punching machine, comprising a plurality of slidable punching pins, a plurality of striker bars each having a striker head with lugs thereon arranged to operate for 110 each striker bar a different combination of said punches, printing type carried on said heads with said lugs, the combination of punches operated by the lugs on the respective striker heads corresponding in code 115 respectively to the characters represented by the type on the said striker heads.

9. A punching machine, comprising a plurality of punching pins, a plurality of movable anvils corresponding in number to said 120 pins and each adapted to engage the head of one of said pins, and a plurality of striker bars each having a striking head arranged to engage a different one or combination of said anvils.

10. A punching machine, comprising a plurality of slidable punching pins, a plurality of anvils adapted to engage the heads

of respective punching pins, means adapted to strike said anvils to operate said pins, and means to shift said anvils out of the path of said pins.

5 11. A punching machine, comprising a plurality of slidable punching pins, a plurality of pivoted anvils adapted to engage the heads of respective punching pins, an adjustable support on which said anvils are 10 mounted whereby they may be withdrawn from operative relation with said pins, and means adapted to strike said anvils to operate said pins.

12. A punching machine, comprising a 15 plurality of punching pins, a plurality of striker bars each having a striking head arranged to operate a different one or combination of said pins, and printing type carried on the striking head of said bars.

20 13. A punching machine, comprising a plurality of punching pins, a plurality of movable anvils corresponding in number to said pins and each adapted to engage the head of one of said pins, a plurality of 25 striker bars each having a striking head arranged to engage a different one or combination of said anvils, printing type carried by the striking heads of said bars, and an adjustable support for said anvils whereby 30 they may be moved from the path of said pins and thereby rendered inoperative by said striker heads in the operation of said striker bars.

14. A punching machine, comprising a 35 plurality of slidable punching pins, a plurality of pivoted striker bars for operating said pins and of greater number than said pins, each of said strikers being provided with means to select predetermined pins for 40 operation, mechanism to operate said striker bars, and power operated automatic means to reset said pins after operation.

15. In a punching machine, the combination with a plurality of freely slidable 45 punches, striking means to operate said punches, power mechanism, a plurality of pivoted striker bars to operate said punches, a stripper plate to strip said punches from the material punched, mechanical connection between said stripper plate and said power mechanisms whereby said stripper plate is moved in one direction to withdraw 50 said pins from the material punched and then moved in the opposite direction to allow said pins to pass freely toward said material.

16. In a perforating machine, the combination with a plurality of punching pins having enlarged heads, a movable stripper 60 plate and a stationary supporting plate in which said pins are freely slidable, a plurality of pivoted anvils, one for each of said pins, said anvils adapted to lie in front of the heads of the respective punching pins, a

plurality of striker bars each having a striking head arranged to engage a different one of said anvils or combination of said anvils and thereby send corresponding punching pins through the article to be perforated, power mechanism, means to operate said 70 striker bars from said power mechanism, positively acting mechanical connection between said stripper plate and said power mechanism whereby said stripper plate is moved in one direction to withdraw said pins 75 from the material punched and then moved in the opposite direction to allow said pins to pass freely toward said material.

17. A punching machine, comprising a plurality of punches, a plurality of pivoted 80 strikers for operating said punches, said strikers each having a head arranged to select predetermined punches for operation, power operated mechanism for operating said strikers, selective mechanism for selecting the desired strikers and coupling same to the power mechanism, and means to operate said selective mechanism.

18. In a machine adapted to impress transverse successive lines of code perforations on a sheet of paper or the like, a plurality of punches, a carriage adapted to carry said paper, means to impart transverse travel to said carriage with respect to said punches, a pivoted striker bar adapted to 95 operate a predetermined combination of said punches, and selective mechanism adapted to control both said carriage operating means and said striker bar.

19. In a machine adapted to impress 100 transverse successive lines of code perforations on a sheet of paper or the like, a plurality of punches, a carriage adapted to carry said paper, means to impart transverse travel to said carriage and said paper 105 with respect to said punches, a space key and mechanism coöperating therewith to control said carriage operating means, and means also controlled by said space key to operate certain of said punches to perforate 110 said paper with a code arrangement of perforations corresponding to the operation of spacing.

20. In a machine adapted to impress transverse successive lines of code perforations on a sheet of paper or the like, a plurality of punches, a carriage adapted to carry said paper, means to impart transverse travel to said carriage with respect to said punches, selective mechanism to control said means, and means controlled by said selective mechanism to operate said punches to perforate said sheet with a code arrangement of perforations corresponding to said operation of said carriage.

115 21. A punching machine, comprising a traveling paper-carrying carriage, a continuously rotating power shaft, spacing

- mechanism to cause said carriage to travel step-by-step, means to mechanically connect the spacing mechanism to the power mechanism, a combination device acting to control the connection between the said spacing mechanism and the said power shaft, selecting means adapted to actuate the combination device, and punching mechanism operated by said power mechanism.
- 10 22. A punching machine, comprising a traveling paper-carrying carriage, a continuously rotating power shaft, spacing mechanism to cause said carriage to travel step by step, means to mechanically connect the spacing mechanism to the power mechanism, a mechanical combination device acting to control the connection between the said spacing mechanism and the said power shaft, selecting means adapted to actuate the combination device, and punching mechanism operated by said power mechanism and controlled by said selecting mechanism.
- 15 23. In a machine adapted to impress transverse successive lines of code perforations on a sheet of paper or the like, the combination with lining mechanism to feed said paper upon said machine from line to line, of punching mechanism adapted to 30 perforate said sheet with a code arrangement of perforations corresponding to the act of feeding the paper up a line.
- 20 24. In a machine adapted to impress transverse successive lines of code perforations on a sheet of paper or the like, a carriage adapted to carry said paper, paper feeding mechanism whereby said paper is fed up from line to line in said carriage, punching mechanism, a lining key, and mechanism coöperating therewith to control the operation of both said paper feeding mechanism and said punching mechanism.
- 25 25. A punching machine, comprising a traveling paper carrying carriage, a continuously rotating power shaft, paper feed mechanism, means to mechanically connect the paper feed mechanism to the power mechanism, a combination device which acts to control the connection between said paper feed mechanism and the said power shaft, selecting means adapted to actuate the combination device, and punching mechanism operated by said power mechanism.
- 30 26. A punching machine, comprising a traveling paper carrying carriage, a continuously rotating power shaft, paper feed mechanism, means to mechanically connect the paper feed mechanism to the power mechanism, a mechanical combination device which acts to control the connection between said paper feed mechanism and the said power shaft, selecting means adapted to actuate the combination device, and punching mechanism operated by said power mechanism and controlled by said actuating means.
- 35 27. The combination of a constantly running power mechanism, a series of punches, a series of strikers operating said punches and greater in number than said punches, a normally in-operative actuating mechanism, means to connect each striker to the actuating mechanism, means to select the striker so connected, said selecting means controlling the coupling of the actuating mechanism to the power mechanism.
- 40 28. In a punching machine adapted to impress transverse lines of code perforations on a sheet of paper or the like, mechanism to feed the paper through the machine from line to line, mechanism to shift the paper transversely for spacing in lines, mechanism to return the paper to the commencement of a new line, keyboard mechanism adapted to control all of said mechanisms, and means controlled respectively by keys of said keyboard to impress on the paper code perforations corresponding respectively to the several operations of feeding, lining and returning of paper above referred to.
- 45 29. In a punching machine, the combination with a continuously rotating power shaft, a traveling paper carrying carriage, punching mechanism normally at rest and adapted at times to operate on said paper, a combination device, and means controlled thereby to connect the punching mechanism to said power shaft.
- 50 30. A punching machine, comprising a plurality of slotted combination bars, selecting means adapted to shift said bars in combinations to bring into alignment prearranged combinations of slots in said bars, a reciprocating actuating device, a plurality of pivoted striker bars, a plurality of punches operated by said striker bars, a plurality of latches adapted to form a positive connection between the said striker bars and the said actuating device, the operation of said latches being controlled by slots in said combination bars, a constantly rotating power shaft, a clutch driven by said shaft and connected to drive said actuating device, an electro-magnet controlling said clutch, and an electric circuit controlled by said combination bars and operating said magnet.
- 55 31. A punching machine, comprising a plurality of slotted combination bars, selecting means adapted to shift said bars in combinations to bring into alignment prearranged combinations of slots in said bars, a reciprocating actuating device, a plurality of pivoted striker bars greater in number than said combination bars, a plurality of punches corresponding in number to said combination bars and operated in combina-

- tions by individual striker bars, a plurality of latches adapted to form a positive connection between the said striker bars and the said actuating device, the operation of 5 said latches being controlled by slots in said combination bars, a constantly rotating power shaft, and means controlled by said combination bars to connect said power shaft to said actuating device.
- 10 32. A punching machine, comprising a keyboard having a plurality of character keys, selector bars operated by individual keys of said keyboard, a plurality of slotted combination bars lesser in number than said 15 keys and movable by said selector bars to bring into alinement combinations of said slots, a plurality of punches corresponding in number to said combination bars, a plurality of pivoted striker bars corresponding in 20 number to said keys and each provided with means adapted to operate a predetermined combination of said punches, power mechanism, and means controlled by said combination bars to effect connection between said 25 striker bars and said power mechanism.
33. A punching machine, comprising punching mechanism, a traveling paper-carrying carriage, spacing, lining and carriage return mechanism, a constantly rotating 30 power shaft, a plurality of clutches adapted to form a part of the mechanical connection between said power shaft and said spacing, lining and carriage return mechanisms, there being one such clutch for each of said 35 mechanisms, and means to control the operation of said clutches.
34. The combination with a plurality of slotted combination bars, selecting means adapted to shift said bars in combinations 40 to bring into alinement prearranged combinations of slots in said bars, a reciprocating actuating device, a plurality of striker bars, a plurality of punches operated in combinations by individual striker bars, a 45 plurality of latches adapted to form a positive connection between the said striker bars and the said actuating device, the operation of said latches being controlled by slots in said combination bars, a constantly rotat- 50 ing power shaft, a clutch driven by said shaft and connected to drive said actuating device, an electro-magnet controlling said clutch, an electric circuit controlled by said combination bars and operating said magnet, a trav- 55 eling paper-carrying carriage, paper lining, spacing and carriage return mechanisms, and a clutch individual to each of these mechanisms and controlled by the said combination bars to effect connection between 60 said power shaft and the said mechanisms.
35. A punching machine, comprising a plurality of punches, power mechanism, means to operate said punches from said power mechanism, a traveling carriage 65 adapted to carry the material to be punched, spacing mechanism for imparting transverse motion to said carriage with respect to the said punches, a clutch to connect said spacing mechanism to the power mechanism, and means to control the operation of said clutch. 70
36. A punching machine, comprising a plurality of punches, constantly operating power mechanism, means to operate said punches from said power mechanism, a traveling carriage adapted to carry the material to be punched, a rotatable spacing screw, means on said carriage adapted to engage the threads on said screw for imparting transverse motion to said carriage with respect to the said punches, a clutch to 75 connect said spacing screw to the power mechanism, and means to control the operation of said clutch.
37. A punching machine, comprising a plurality of punches, power mechanism, means to operate said punches from said power mechanism, a traveling carriage adapted to carry the material to be punched, lining mechanism for feeding said material up from line to line in said carriage, a clutch to connect said lining mechanism to the said power mechanism, and means to control the 80 operation of said clutch.
38. A punching machine, comprising a plurality of punches, punch operating mechanism, power mechanism, means to connect the power mechanism to the said punch operating mechanism, a traveling carriage adapted to carry the paper or other material to be punched, a paper feed roller carried 85 by said carriage, a lining shaft adapted to rotate said roller and upon which said roller is mounted for longitudinal movement, a clutch adapted to connect said power shaft to the said lining shaft, and means to operate said clutch. 90
39. A punching machine, comprising a plurality of punches, punch operating mechanism, power mechanism, means to connect the power mechanism to the said punch operating mechanism, selective mechanism controlling said connection, a traveling carriage adapted to carry the paper or other material to be punched, a paper feed roller carried 95 by said carriage, a lining shaft adapted to rotate said roller and upon which said roller is mounted for longitudinal movement, a clutch having a normally rotating member connected to said power mechanism and a normally stationary member connected to 100 said lining shaft, and means controlled by said selective mechanism to couple and uncouple said clutch members. 110
40. A punching machine, comprising a plurality of punches, a plurality of pivoted striker bars for operating said punches in combinations, power mechanism, means to connect the power mechanism to the said 120

- striker bars, selective mechanism controlling said connection, a traveling carriage adapted to carry the paper or other material to be punched, a paper feed roller carried by said carriage, a lining shaft adapted to rotate said roller and upon which said roller is mounted for longitudinal movement, a clutch having a normally rotating member connected to said power mechanism and a normally stationary member connected to said lining shaft, and means controlled by said selective mechanism to couple and uncouple said clutch members.
41. A punching machine, comprising punching mechanism, a traveling carriage adapted to carry the material to be punched and in which said material is movable past the punching point, carriage spacing mechanism adapted to shift the carriage in a direction transverse to the direction of the movement of the said material in said carriage, power mechanism, and key controlled means to connect the carriage spacing mechanism and the punching mechanism to said power mechanism.
42. A punching machine, comprising punching mechanism, a traveling carriage adapted to carry the material to be punched, carriage spacing mechanism, carriage returning mechanism comprising a rotatable shaft having a spiral thereon adapted to engage said carriage, a constantly rotating power shaft, and a clutch arranged to couple said power shaft to said carriage returning shaft.
43. A punching machine, comprising punching mechanism, a traveling carriage adapted to carry the material to be punched, carriage spacing mechanism, carriage returning mechanism comprising a rotatable shaft having a spiral thereon adapted to engage said carriage, a constantly rotating power shaft, a clutch arranged to couple said power shaft to said carriage returning shaft, lining mechanism to feed the said material in said machine, and means operated by the return of the carriage to the commencement of its travel to automatically operate the said lining mechanism.
44. A punching machine, comprising a plurality of punches, power mechanism, means to operate said punches from said power mechanism, a traveling carriage adapted to carry the material to be punched, lining mechanism for feeding said material up from line to line in said carriage, a clutch to connect said lining mechanism to the said power mechanism, and means to control the operation of said clutch, blanking mechanism operating the lining clutch and its associated parts to feed the said material in the machine a plurality of line spaces at a higher rate of speed than that at which the lining mechanism normally operates, and means to automatically stop said blanking

mechanism when the paper has been fed up a predetermined distance.

45. A punching machine, comprising punching mechanism, a power shaft and means to operate said punching mechanism from said power shaft, a traveling carriage adapted to carry the material to be punched, a roller carried by said carriage and adapted to feed said material in said machine, a lining shaft adapted to rotate said roller and upon which said roller is mounted for movement longitudinally thereof, a lining clutch having a normally rotating member connected to said power shaft and a normally stationary member connected to said lining shaft, means to operate said last named clutch, a rotatable backing shaft having a spiral thereon adapted to engage a portion of said carriage to return the same to the commencement of its travel, a backing clutch having a normally rotating member connected to said power shaft and a normally stationary member connected to said backing shaft, means to operate said backing clutch, automatic means to operate said lining mechanism by the return of said carriage to the commencement of its travel.

46. A punching machine, comprising a plurality of punches, a plurality of striker bars, a power shaft and means to operate said striker bars from said power shaft, a traveling paper-carrying carriage, a rotatable spacing screw shaft, means on said carriage adapted to engage said spacing screw to impart step-by-step transverse motion to said paper and carriage with respect to said punches, a spacing clutch having a normally rotating member connected to said power shaft and a normally stationary member connected to said spacing screw shaft, electrically operated means to control the coupling of the normally stationary members on said clutch, a contact device adapted to initiate the operation of said electrical operating means, a paper feeding roller carried by said carriage, a lining shaft adapted to rotate said roller and upon which said roller is mounted for movement longitudinally thereof, a lining clutch having a normally rotating member connected to said power shaft and a normally stationary member connected to said lining shaft, means to control the coupling of the said members of said last named clutch, a rotatable backing shaft having a spiral thereon adapted to engage a portion of said carriage to return the same to the commencement of its travel, a backing clutch having a normally rotating member connected to said power shaft and a normally stationary member connected to said backing shaft, means to effect the coupling together of said members of said backing clutch, and automatic means to operate said lining mechanism by the return of said carriage to the commencement of its travel.

47. A punching machine, comprising a plurality of punching pins, a plurality of striker bars each having a striking head arranged to select and operate a different one or combination of said pins, printing type carried on said striker bar heads, and adjustable means for rendering said pins inoperative by said striker heads at will for causing the machine to print without perforating.

48. A punching machine, comprising a plurality of punching pins, a plurality of striker bars greater in number than said pins, said striker bars comprising each a head having means to select and actuate a given combination of said pins, and means to operate said striker bars.

49. A punching machine, comprising a series of punches, a series of punch operating members of greater number than said punches and of which one at a time is to be selected, there being one such punch operating member for each individual character or code arrangement of perforations to be impressed, a mechanical combination device comprising a series of movable combs corresponding in number to said punches, and adapted to select the said members to be operated, and selecting means to operate said combs in the desired combinations.

50. A punching machine, comprising a series of punches, a series of punch operating members of greater number than said

punches and of which one at a time is to be selected, a mechanical combination device comprising a series of movable members corresponding in number to said punches, a plurality of keylevers one for each of said punch operating members, and permutation means whereby the operation of a given keylever operates a predetermined one or combination of said members of said mechanical combination device to select the desired punch operating member to be actuated.

51. A punching machine, comprising a series of punches, a series of punch operating members of greater number than said punches and of which one at a time is to be selected, a mechanical combination device comprising a series of movable combs corresponding in number to said punches, and adapted to select the punch operating members to be operated, a plurality of keylevers one for each of said punch operating members, and permutation means whereby the operation of a given keylever operates a predetermined one or combination of said combs.

In testimony whereof I affix my signature in presence of two witnesses.

LOUIS MAXWELL POTTS.
